(57) **CLAIM**

The ornamental design for a container holder as shown and described.

DESCRIPTION

FIG. 1 is a front view of a container holder showing our new design;

FIG. 2 is a rear view thereof;

FIG. 3 is a right side view thereof;

FIG. 4 is a left side view thereof; and,

FIG. 5 is a top, front, left perspective view showing our new design of FIGS. 1-4 in an exemplary environment.

The broken lines immediately adjacent to the shaded area define the bounds of the claimed design and form no part thereof. The broken lines depicting the remainder of the container holder form no part of the claimed design.
